UNITED STATES PATENT OFFICE.

ARTHUR R. FORS, OF DETROIT, MICHIGAN, ASSIGNOR TO CONTINENTAL MOTORS CORPORATION, OF DETROIT, MICHIGAN, A CORPORATION OF VIRGINIA.

STEADY REST FOR GRINDING MACHINES.

Application filed August 30, 1920. Serial No. 406,916.

To all whom it may concern:

Be it known that I, ARTHUR R. FORS, a citizen of the United States, residing at Detroit, in the county of Wayne and State of Michigan, have invented a new and useful Improvement in Steady Rests for Grinding Machines, of which the following is a specification.

My invention relates to an improved form 10 of steady rest for grinding machines, by which the work being ground may be positively and accurately supported intermediate its ends and furthermore my device is constructed so that all adjustments required 15 to correctly place and secure the parts of the steady rest in exact position may be positively and conveniently accomplished.

My invention will best be understood by reference to the accompanying drawings, 20 showing a preferred embodiment thereof, in which:

Fig. 1 shows the steady rest in side elevation and partially in section in the position it assumes when in use on a grinding machine; and

Fig. 2 is a front elevation of the parts shown in Fig. 1 as seen from the right hand of said figure.

Fig. 3 is a sectional view of part of the 30 construction shown in Fig. 2 taken along the line 3—3.

Similar numerals refer to similar parts throughout the several views.

As shown in the drawings my improved 35 steady rest consists of a housing 10 through which a bolt 11 extends, said bolt having at its far end a square head which when the steady rest is in use is in a T-shaped slot 13 shown in Fig. 2, longitudinally and horizontally of a supporting part 14 of the grinding machine convenient to the work 32 being ground to support desired devices adjacent the work.

The housing 10 is provided with a vertical slot 15 in which a support 16 fits so as to be capable of vertical motion in said slot. The rear face of the support 16 is beveled as indicated at 17 and fits a corresponding bevel on the outer surface of a wedge 18 also fitting slot 15 for vertical motion therein. The rear face of the wedge 18 rests against the flat surface of the portion 14 of the grinding machine. Screws 19 and 20 extend through the upper portion of the housing 50 55 10 into the upper end of the slot 15 and at

their lower ends are threaded respectively into the upper ends of the support 16 and the wedge 18. The support 16 and the wedge 18 have formed through them slots 21 and 22 to receive a bolt 23 similar to the 60 bolt 11 and having a square head 12 similarly engaging the slot 13. The lower end of the support 16 is preferably curved as indicated and carries on its inner surface a bushing 24 accurately finished on its inner 65 surface to engage the work 32 being ground, said bushing being held in place on the support by having formed therein on its outer surface a shallow groove 25 equal in width to the width of the support 16 said parts being 70 further held in said engagement by a pin 26 and a retaining plate 27.

The housing 10 is further held in proper position on the part 14 by a key 28, secured to said housing by a screw 29 so that by the 75 engagement of said key with the narrower part of the slot 13 as more clearly shown in Fig. 3, the housing is retained in proper position when the bolt 23 is loosened to adjust the support 16 and the bushing carried 80 thereby to proper position.

In using the steady rest, the housing 10 is first secured to the part 14 at a position on the work 32 such that the bushing when 85 adjusted will engage a part of the work 32 that is not to be ground for this particular adjustment of the steady rest. At this time, the bolt 23 is released from clamping position and the housing 10 is held in place by the bolt 11 and the key 28. The support 16 90 is then moved vertically until the bottom part of the bushing 24 engages the surface of the work 32 and then the wedge 18 is moved vertically until the upper part of the bushing 24 is in proper engagement with the work 32, after which the support and wedge are securely clamped to the part 14 of the grinding machine by tightening the bolt 23. It will be observed that the support 95 100 105 110

16 affords a means for adjusting the bushing 24 vertically and that the wedge 18 affords a means for adjusting the bushing horizontally and that a suitable clearance 30 is provided in the upper portion of the housing 10 to permit horizontal movement of the screw 19 in the housing as required by the adjustment of the wedge 18 so that when the bolt 23 is tightened the bevel faces of the support 16 and the wedge 18 and the rear face of the wedge 18 and the corresponding 110

face of the part 14 are held positively together throughout the entire extent of the said surfaces of the support 16 and the wedge 18. For this condition the bolt 23 5 also serves to prevent displacement of the housing 10 on the part 14 of the grinding machine, as a result of the fit of the support 16 and the wedge 18 in the slot 15 and the further fact that the screws 19 and 20 are 10 preferably made close fits in the support 16 and wedge 18 and provided with flanges for preventing longitudinal motion of said screws in the housing 10. As a result of the construction described it will be observed 15 that the thrusts exerted upon the work 32 by the grinding wheel 31 moving in the direction indicated, are directed substantially towards the mid portion of the bushing 24 and that therefore the work is positively 20 supported so that it will not spring away from the wheel 31 as a result of the grinding operation and thus cause the work to chatter. The steady rest may obviously be moved to any position longitudinally of the 25 grinding machine that may be required and various bushings 24 may be used with the same support 16 if necessary to fit parts of the work 32 of different diameter.

While I have shown my invention in the 30 particular embodiment above described I do not however, limit myself to this exact construction, as I may employ modifications thereof known to the art at the time of the filing of this application without departing 35 from the scope of the appended claims.

What I claim is:

1. In a device of the class described, the combination of a housing adapted to be rigidly supported, a support carried by the 40 housing, a bushing carried by the support to fit the work being ground, means for moving the support relatively to the housing to bring the bushing into engagement with the work being ground, devices for rigidly 45 clamping the support in any desired adjustment, the rear face of said support being beveled, a correspondingly beveled wedge engaging said beveled face of the support, and means for moving said wedge relatively 50 to said housing to engage said support in any of its desired positions.

2. In a device of the class described, the combination of a housing adapted to be rigidly supported, a support carried by the 55 housing, a bushing carried by the support to fit the work being ground, a screw between the housing and support for moving

the latter as desired relatively to the former, a clamping bolt extending through said support, the rear face of said support being 60 beveled, a correspondingly beveled wedge engaging said beveled face of the support, and a screw between said housing and said wedge for moving the latter as desired relatively to the former, said clamping bolt also 65 rigidly holding said wedge in desired position.

3. In a device of the class described, the combination of a housing adapted to be rigidly supported, a support carried by the 70 housing, a bushing carried by the support to fit the work being ground, a screw between the housing and support for moving the latter as desired relatively to the former, a clamping bolt extending through said support, the rear face of said support being 75 beveled, a correspondingly beveled wedge engaging said beveled face of the support, a screw between said housing and said wedge for moving the latter as desired relatively to the former, said clamping bolt also rigidly holding said wedge in desired position, and a second clamping bolt for rigidly holding 80 said housing in desired position, said support and wedge having a sliding fit in a slot provided therefor in said housing.

4. In a device of the class described, the combination of a housing adapted to be rigidly supported, a support carried by the 85 housing, a bushing carried by the support to fit the work being ground, a screw between the housing and support for moving the latter as desired relatively to the former, a clamping bolt extending through said support, the rear face of said support being 90 beveled, a correspondingly beveled wedge engaging said beveled face of the support, a screw between said housing and said wedge for moving the latter as desired relatively to the former, said clamping bolt also rigidly holding said wedge in desired position, a second clamping bolt for rigidly holding 95 said housing in desired position, said support and wedge having a sliding fit in a slot provided therefor in said housing, and a key carried by said housing and projecting therefrom for preventing rotation of said housing relatively to its support when in place on a grinding machine.

In witness whereof, I hereunto subscribe my name this 17th day of August, A. D. 1920.

ARTHUR R. FORS.
